UNITED STATES PATENT OFFICE.

ALFRED W. LUBLIN, OF BOSTON, MASSACHUSETTS.

DESIGN FOR A DRESS-STAY.

SPECIFICATION forming part of Design No. 27,494, dated August 3, 1897.

Application filed June 28, 1897. Serial No. 642,751. Term of patent 14 years.

To all whom it may concern:

Be it known that I, ALFRED W. LUBLIN, a citizen of the United States, residing at Boston, county of Suffolk, State of Massachusetts, 5 have invented a certain new and original Design for the Bodies of Dress-Stays, of which the following is a full, clear, and exact description.

My design is illustrated by the accompanying drawing, which is an enlarged plan view 10 of a portion of a dress-stay illustrating my design.

The leading feature of my invention is the 15 design for the surface ornamentation of the body portion of a dress-stay, which ornamentation comprises a parallel series of dia-

nally-arranged scrolls A A upon the body B of the dress-stay, the configuration of the said scrolls, together with the arrangement of the same, producing the effect of parallel spiral 20 columns when the stay is held so as to be viewed in an upright position.

What I claim is—

The design for the body of a dress-stay, as herein shown and described.

Signed at Boston, in the county of Suffolk and State of Massachusetts, this 16th day of June, 1897.

A. W. LUBLIN.
